EMERGENCY LANDING FLARE AND RE-
LEASING DEVICE THEREFOR

Samuel Wiley, Metuchen, N. J.

Application February 13, 1933, Serial No. 656,596

9 Claims. (Cl. 102—24)

The present invention relates to emergency landing flare and releasing device therefor, and has for an object to provide a flare and releasing device in which the flare may be safely carried 5 in air craft, and from which, when desired, the flare may be released to descend slowly through the air and illuminate the ground and other objects beneath the air craft.

The invention is not only intended for use in illuminating hostile territory, troops and the like, but is especially adapted for use in making night landings by air craft on peaceful missions such as; the landing of hydroplanes in harbors; and the landing of aeroplanes on the ground, and for 15 use in general to brilliantly illuminate a considerable area of land or water used for shipping, building and the like.

Another object of the present invention is to provide an improved ignition device for the flare 20 which may be quickly and easily and safely assembled in the manufacture of the flare and which provides for a positive ignition of the fuse when the ignition device is actuated by the parachute subsequent to launching of the flare.

A further object of the invention is to provide 25 a flare with a carrying case in which the flare may be mounted for transportation from its point of manufacture to the landing field, or the like, where the flares are to be installed, and to provide a socket plate of relatively light and small 30 construction adapted to receive the flare with its carrying case so that the carrying case may serve as a launching tube when the flare is released from the air craft or other carrying body.

A further object of the invention is to provide 35 an improved means for retaining the flare in the carrying case during transportation of the flare and to provide improved means carried by the socket plate for cooperation with the retaining 40 means of the carrying case to release the flare at the desired time of launching so as to positively eject the flare from the carrying case when serving as a launching tube.

The invention still further aims to provide an 45 improved retaining and releasing means for the flare in the carrying case which may be securely locked against accidental release during the shipping or transportation of the flare and which embodies features necessitating the unlocking of the 50 releasing means prior to the mounting of the flare in the socket plate.

The invention further aims to provide an improved releasing device carried by the socket plate adapted to first unlatch the holding device 55 on the carrying case and to subsequently posi-

tively release the retaining device to insure the freedom of the flare at the time of launching.

With the foregoing and other objects in view, the invention will be more fully described herein-after, and will be more particularly pointed out 5 in the claims appended hereto.

In the drawings, wherein like symbols refer to like or corresponding parts throughout the several views.

Figure 1 is a side elevation partly in section of 10 a flare mounted in its carrying case embodying the features of the present invention.

Figure 2 is a top plan view of the same.

Figure 3 is a similar view with the flare removed and showing the bottom retaining device 15 partly released.

Figure 4 is a fragmentary vertical section taken through the lower end of the flare in its carrying case and in locked position.

Figure 5 is a similar view showing the retaining 20 device released and partially removed, the dotted lines showing the full releasing position of the retaining device.

Figure 6 is a vertical central section taken through the flare constructed according to the 25 present invention.

Figure 7 is an enlarged detail sectional view taken through the ignitor.

Figure 8 is a detail perspective view of the 30 same with the parts in position of operation.

Figure 9 is a top plan view thereof.

Figure 10 is a side elevation of the flare operating position after launching.

Figure 11 is a top plan view of a socket plate 35 adapted to be mounted on air craft or other supporting body.

Figure 12 is an edge elevation of the same.

Figure 13 is an enlarged fragmentary view of 40 one end of the socket plate having a flare with its carrying case mounted therein.

Figure 14 is a side elevation of the same, the upper portion being broken away.

Figure 15 is a like view taken axially at right angles to Figure 14.

Figure 16 is a top plan view of a modified form 45 of socket plate with a flare mounted therein in horizontal position.

Figure 17 is a side elevation of the same, and

Figure 18 is a transverse section taken through the modified device on the line 18—18 of Figure 50 17.

With reference first to Figure 6 of the drawings, the flare comprises a metallic cylindrical casing 25 which is fitted at its lower end to a combustible casing 26 which carries therein the 55

illuminating composition 27. This composition 27 is pyrotechnic in character and of combustible chemicals which when ignited burn at a high temperature so as to give off brilliant light. This 5 composition 27 is inherently dense and is difficult to ignite with an ordinary flame. To insure ignition, a combustible composition 28, which will burn with a high temperature, is charged on the lower end of the illuminating composition 27, 10 and to those skilled in the art it is known as the auxiliary or starting fire composition. While various compositions are used for the starting fire composition, it is preferred to use a composition including the original illuminating composition 15 with a percentage of a granular substance, as shown in Figure 6, which in itself has a very low ignition point but burns at a high temperature. This causes the starting fire composition to ignite from a flame of relatively low temperature. 20 fire composition by means of pieces of quick-match 29 held in place against the starting fire composition 28 by means of a paper disc 30.

The lower end of the combustible casing 26 is closed by means of a cap 31 which fits against 25 the disc 30 and holds all of the parts in place. The combustible casing 26 is provided at preferably its central portion with an axial tube 32 through which a strand of quick-match 33 is carried, the lower end of the strand of quick- 30 match 33 held by the disc 30 against the auxiliary firing composition 28 and in contact with the pieces of quick-match 29. The upper end of the strand of quick-match 33 is over-turned from the tube 37 and lies in a chamber 34 formed in the 35 underside of a head block 35 mounted in the upper end of a combustible casing 26 by means of screws 36 or the like. It will be noted that the screws 36 also engage through the lower end of the metallic casing 25 so as to secure the upper 40 and lower casings together as a unit.

The head block 35 detachably carries the igniter and for this purpose is provided with a relatively large axial opening. The igniter, as best shown in Figures 7, 8 and 9, comprises a preferably metallic tube 37 slidably fitting in the opening of the head block 35 and adapted to project downwardly therethrough.

The lower end of the tube 37 is open to expose the interior thereof to the upper end of the 50 quick-match strand 33. An attaching plate 38 is secured across the upper end of the tube 37 and projects therebeyond to provide a pair of ears which are apertured to receive bolts 39, or the like, which are carried by the block 35 to clamp the ears flat against the upper side of the block and with the tube 39 inserted in the block.

A disc 40 is fitted in the upper end of the tube 37 and a friction disc 41 is arranged above the disc 40 and may, as shown in Figure 7, be in the form 55 of a cap which encloses the marginal portion of the disc 40 and has its lower edge over-turned therebeneath to unite the discs 40 and 41. The disc 41 is of relatively thin metal, cardboard or the like which admits of the tearing of the device when the flare is launched and when the jerk of the parachute is applied thereto as will be later brought out. The disc 40 is provided with a pair of spaced openings therethrough which are lined with a coating of a primer powder 60 42 for cooperation with a friction composition 43 which is coated upon loops of wires which extend downwardly through the openings in the disc 40. Two of these friction wires are shown.

Each friction wire has one end clamped between the discs 40 and 41 and from that end

extends downwardly through one of the openings of the disc 40, is curved into a loop disposed in the lower end of the tube 37, and is thence returned back through the opening in the disc 40 and along the upper face of the disc 40 beneath the disc 41, the discs clamping the ends of the loop firmly against the upper side of the disc 40. The wire 44 is carried upwardly through a central opening 45 which is formed in the friction disc 41 at the central portion thereof so as to hold the wire 40 with substantially right angular bends as it passes through and between the discs 40 and 41. The two wires 44 are brought together at the opening 45 of the friction disc and carried upwardly therefrom as a cable or 10 single strand. When this strand 44 is jerked upwardly with sufficient force, it will tear through the friction disc 41, as shown in Figure 8, and thence the friction composition loops 43 may be drawn upwardly through the openings in the 20 disc 40 to cooperate with the primer powder and thus produce a substantial flame within the lower end of the tube 37.

This flame ignites the upper end of the quick match strand 33 so as to ignite the flare.

Secured to the upper side of the attaching plate 38 in co-axial relation with the tube 37 is a cup 46 having the bottom thereof at its central portion raised or dished upwardly to provide a dome 47 with a cavity therebeneath disposed over the central portion of the friction disc 41 to admit the upward tearing of the disc and to accommodate the wires 44 when they are drawn taut after release from the disc 41. The dome 47 therefore admits of the free pulling of the 35 wires 44 upwardly through the disc 40 so as to draw the friction composition loops 43 upwardly through the openings. The dome 47 has a central opening at its top through which the wires 44 project, and through which also extends a 40 parachute cable 48, the lower end of the cable being closed and secured between the bottom of the cup 46 and the attaching plate 38 as shown in Figure 7.

The parachute cable 48 is adapted to be wound 45 in the cup 46, and the latter is provided with a cap 49 through which the upper end of the cable extends, the cable preferably extending through the cap near one edge thereof and adapted for attachment to a second cable 50 which extends 50 to the parachute.

From Figure 7 it will be noted that the lower end of the cable 48 is looped or slackened so that the weight of the flare when taken up by the parachute is through the wires 44.

The advantage of this construction of igniter is that it may be assembled and completely set up, is mounted in the head block 35 of the flare and thus there is no danger of setting off the flare during the assembling of the parts of the igniter.

The upper cable 50 is connected to a parachute, 51 which is folded within the upper metallic casing 25 and which is provided upon its upper end with a weight 52 in the form of a disc, or the like, secured to the parachute. The weight 52 is adapted to fly out of the upper open end of the casing 25 and draw the parachute therewith when the flare is first released from the air craft, the flare turning over or spinning to effectively 60 project the weight 52 out of the casing 25.

Referring now to Figures 1 to 5, the parachute, after it has been made up as shown in Figure 6, is placed in a carrying case 53 which may comprise a metal tube open at its upper end and

provided with an out-turned flange 54 at its lower end, which may be mounted on the carrying case 53 by means of a band or ring 55 secured about the lower end portion of the carrying case. 5 The carrying case 53 is of larger diameter than that of the flare so that there is an annular space between the casing and the flare which admits of the free and easy introduction and removal of the flare through the lower end of the carrying case. 10 The flare is maintained steady and centralized in the carrying case at the upper end by means of a top cover 56 preferably of metallic construction and having a central depressed part fitting into the upper open end of the flare to 15 hold the weight 52 of the parachute in place. The cover 56 has a flange at its outer edge which overlaps the upper end of the carrying case 53 and may be soldered or otherwise suitably secured thereto. The cover 56 has a somewhat 20 loose fit in the upper end of the flare so that the latter may fall downwardly away from the cover 56 when the flare is released at its lower end.

A bottom cover or closure 57 is fitted in the lower end of the carrying case 53 and is provided 25 with a depressed central portion into which is seated the lower cap 31 of the flare, as shown in Figure 4. The lower cover 57 is provided with an annular spacing bead which lies between the carrying case and the flare so that the lower 30 end of the flare is centered in the carrying case. The closure 57 is provided with an outstanding flange 58 which lies beneath the flange 54 of the carrying case and which at one side is provided with a curved tongue 59 which enters the slot 60 35 in one side of the flange 54 so that the cover 57 is hingedly connected at one side of the carrying case to the latter and may be swung downwardly to open the lower end of the carrying case, as shown in Figure 5. The lip 59 is preferably 40 curved or of arcuate form so that it will readily slide out of the slot 60 when the cover 57 is swung down to a substantially vertical position, when the cover 57 may fall away from the carrying case and free the flare.

45 The lower cover plate 57 is provided in one side, preferably opposite to the lip 59 with a keeper slot 62 spaced above the flange 58 a distance equal substantially to the thickness of the flange 54 of the carrying case so that the slot 62 will be exposed above the flange 54 when the lower cover 57 is in place. A latch lever 63 is pivoted at one end upon a rivet 64, or the like, on the upper face of the flange 54 in position to swing in an edgewise direction at its free end toward and from the slot 62. A lip 65 is provided 50 on the inner edge of the latch lever 63 and is proportioned to project into the slot 62, and preferably has its inner free edge curved to escape the depressed central portion of the cover 55 60 57, as shown in Figure 4. The latch lever 63 is releasably held in locked position to hold the cover 57 closed by means of a frangible pin 66 adapted to be sheared off when the latch lever 63 is forced outwardly into the position shown in Figure 3. For the purpose of handling the carrying case with the flare therein and to prevent the accidental opening of the latch lever 63, a cotter pin 67 may be fitted through the latch 63 and the flanges 54 and 58, and may have a 65 ring 68 through its upper end to facilitate removal of the cotter pin 67 by manual force just prior to the mounting of the parachute with its carrying case in an aeroplane or the like.

70 The frangible pin 66 also engages through the flanges 54 and 58 and is adapted to remain in

position until the latch lever 63 is forced into open position by the releasing mechanism hereinafter described. Thus, the latch lever 63 cannot be accidentally opened either during the handling and shipping of the complete device, or even after the device is mounted in launching position upon the air craft or carrying body.

75 The flange 58 of the cover 57, beneath the latch 63 is imperforate. The flange 54 of the carrying case is provided with a slot 69 which may be of circular form as shown. The latch lever 63 is provided with an opening 70 therethrough adapted to align with the opening 69 in the flange 54 only when the latch 63 is swung into an open position, as shown in Figure 3. 10 This opening 70 in the latch may be rectangular or of any other suitable configuration for receiving a releasing and ejecting pin later described, and at its outer marginal edge is provided with a notch 71 forming a shoulder or seat 15 for the lower end portion of the said pin when the latch lever 63 is closed, as shown in Figure 2. The slot 70 is therefore offset inwardly out of line with the opening 69 when the latch lever 20 is in closed position and the notch 71 is located substantially coaxial with the circular slot 69. The result is that the passage downwardly 25 through the slot 69 is at least partly closed so that the releasing and ejecting pin cannot move downwardly until the latch lever 63 is retracted. 30

35 Referring now to Figures 11 to 15, the aeroplane or other body or support from which the flares are adapted to be launched, is provided with a socket or launching plate 72. This plate 72 is relatively thin and is provided with an opening 73 therethrough for each flare to be carried. Figures 11 and 12 show a socket plate provided with three such openings, and each opening with its adjacent parts is identical and may be repeated any desired number of times, or only 40 one such opening may be used where found necessary, and depending upon the number of flares to be carried.

The socket opening 73 is of sufficient size to 45 freely receive the carrying case 53 which is adapted to be moved upwardly through the opening 73. The socket plate 72 is secured in horizontal position to any adaptable portion of the air craft. The socket plate 72 is provided around the opening 73 with a plurality of threaded openings 74, the walls of which may be reinforced by bosses or projections provided on the upper surface of the plate 72 as shown, and these openings 74 are adapted to receive upwardly therein binding screws 75 which first pass upwardly 50 through openings 76 provided in the flange 54, the flange 58 of the cover plate 57 being cut away or recessed at points adjacent these openings 76, as shown in dotted lines in Figure 2.

55 The heads of the screws 75 bear against the lower side of the flange 54 and hold the flange in tight engagement against the under side of the socket plate 72. The carrying case 53 when thus inserted in the plate 72 and secured by the screws 75 becomes a launching tube and substantially a permanent part of the socket plate 72.

60 For each socket opening 73, the plate 72 is provided with a launching or releasing device for the flare. Each device comprises an upstanding 65 bracket 77 which is disposed near the edge of the plate 72 and is forked at its upper portion to accommodate a bell crank lever 78 which has a shoulder 79 at the outer side of a pivot 80 connecting the lever 78 to the bracket 77. The bight 75

- of the upper forked end of the bracket 77 provides a stop shoulder 81 against which the shoulder 79 of the lever is adapted to normally rest for determining the normal position of the lever.
- 5 The lever 78 is provided with one or more arms 82 which extend in the desired direction from the pivot 80 and are suitably apertured for the reception of a releasing cable, or the like, so that the cable may be carried either in a general horizontal or a general vertical direction from the lever 78, depending upon the point from which the cable is to be controlled.
- 10

The bracket 77 is provided at its inner side with a vertically apertured lug 83 through which is slidably mounted a combined latch releasing cover ejecting pin 84 having a headed upper end beneath which is placed a coil spring 85 surrounding the pin 84 and resting upon the lug 83. The spring 85 holds the pin 84 in raised position as shown in Figures 12 and 14. The lever 78 is provided with a rounded or cam head 86 which bears upon the head of the pin 84, and when the lever 78 is turned on its pivot 80 it is adapted to depress the pin to launch the flare. The plate 72 is provided at its under side with a recess 87 for accommodating the latch lever 63, and the recess 87 may be carried across the plate 72 to the opposite side of the opening 73 thereof, as shown in dotted lines in Figures 11 and 13 to accommodate a second latch device, should it be found necessary or desirable to use the same. But one latch mechanism is shown in the present case for the sake of clearness although any desired number may be used depending upon the weight of the flare and other conditions which may be met with incident to the installation and use of the device.

The opening in the lug 83 extends downwardly through the plate 72 in register with the slot 69 in the carrying case flange 54, as shown in Figures 13, 14 and 15.

The lower end of the launching pin 84 is tapered or otherwise reduced in diameter so as to first enter the notch 71 of the latch 63 and to be held by the shoulder about the notch from further downward movement until considerable pressure is inserted upon the upper end of the pin to force it downwardly. The pin 84, above its tapering point, is of a size to freely pass downwardly through the slots 70 and 69 when the latch 63 is released so that the lower end of the pin may engage the flange 58 of the lower cover 57 and force the latter downwardly and outwardly into open position, as shown in Figure 15. The movement of the pin 84 is proportioned to eject the lower cover 57 a distance such that the cover will fall out of the lower end of the carrying case by its own weight and will not stick or jam, the weight of the flare supported on the lower cover 57 being sufficient to move the cover 57 entirely out of the case after the initial releasing movement thereof.

In use and operation, the flare of Figure 6 is assembled by first building up the lower cylinder 26 with its charge and strands and with the head block 35 mounted in position. The igniter is assembled as a separate unit, as shown in Figure 7 and is then fitted through the top of the block and secured thereto by the devices 39.

70 Of course these devices 39 may be screws, or any other suitable fastening means freely accessible and operable from the top of the block 35. The parachute portion of the flare is now folded and fitted in the upper casing 25, and the flare thus formed is placed in the carrying case 53 with

the top cover 56 fitted to the carrying case and the top of the flare, and with the lower cover 57 fitted in the bottom of the case and about the lower end of the flare. The latch lever 63 is forced inwardly to engage in the slot 62 of the lower cover and the frangible pin 66 and the cotter pin 67 are then in position so as to securely hold the flare within its carrying case and prepare the latch for final operation. The flare in this carrying case may thus be safely shipped to an airport, or other place for use and upon arrival, it is only necessary to withdraw the cotter pin 67 with its ring 68 and to slide the entire unit, including the carrying case 53 upwardly through the opening 73 in the socket plate 72 and secure the parts together as a unit by means of the screws 75. The flare is thus encased and is protected against the weather and foreign substances by the upper cap 56 and the lower cap 57.

When it is desired to launch the flare, it is only necessary to operate the bell crank lever 78, as above described, or depress the head 86 thereof against the pin 84 and against the tension of the spring 85. The initial downward movement of the pin 84 moves the tapering end thereof downwardly in the notch 71 and forces the latch lever 63 outwardly, breaking off the frangible pin 66 and moving the slot 70 of the latch into register with the slot 69 of the flange 54. As the pin 84 continues its downward movement, it passes through the latch 63, moving the same outwardly and out of engagement with the keeper slot 62, and the lower end of the pin bears against the flange 58 of the lower cover and forces the latter downwardly and out of the carrying case 53. This releases the flare so that the latter by its weight swings the lower cover 57 out of the way where it may fall by release of the curved tongue 59, and at the same time the flare falls away from the upper cover 56 on account of the relatively loose fit of the central portion of the cover in the top of the parachute casing 25.

As soon as the flare is freed from the carrying and launching tube 53, the weight 52 is projected out of the flare and draws with it the parachute 51 so that the latter is subjected to the air pressure and is readily opened. As the parachute takes up the weight of the flare on the cables 50 and 48, the wires 44 are drawn taut and take up the weight of the flare with the result that these wires are torn through the friction disc 41 and straightened out from more or less directly with respect to the openings 42 in the disc 40. The friction loops 43 are thus drawn upwardly through the openings 42 and into contact with the ignition lining of the openings 42. The resultant flash is projected downwardly in the tube 37 and against the quick-match strand 33, igniting the flare. After the wires 44 have been drawn upwardly from the disc 40 the lower slack end of the cable 48 is drawn taut and it carries the flare directly from the parachute 51.

Referring now to the modification shown in Figures 16, 17 and 18, it is desirable at times to mount the flare with its axis horizontal and in the under side of an aeroplane wing or other location where the height of a flare prohibits its mounting.

In the modification the socket plate 88 is adapted to be mounted horizontally on an air craft, or the like, and is secured by the screws 89 to the carrying and launching case 90 which, in the present instance, is lengthwise in a horizontal direction and opens downwardly at its lower side for receiving therein the flare shown in Figure 6.

In Figure 18 the flare is indicated at 31, being the bottom cap as shown in Figure 6. The casing 90 has a lower cap or closure plate 91 which along one edge may be connected by hinges 92, or the like, to the socket plate 88. The flare is provided intermediate its ends with an annular groove 93 and the casing 90 is provided in its upper side and intermediate its ends with a depressed rib 94 adapted to enter the groove 93 of the flare for holding the latter against longitudinal or side shifting in the casing 90 and to insure the even movement or dropping of the flare at opposite ends from the casing 90 when the cover 91 is released. The cover 91 is held in place by the same mechanism and in the same manner as is disclosed in Figures 13, 14 and 15. The free edge of the cover 91 has the downwardly offset and outwardly extending flange 58 while the casing 90 carries the outstanding flange 54 with the latch lever 63 thereon as above described.

When in this horizontal position, it is preferable to employ a latch 63 at each end of the casing 90, and each latch 63 is provided with its releasing and cover ejecting pin 84 actuated upon the depression of the cams 86, and as a pair of these cams is used, the bell crank levers 95, carrying the cams 86, are provided only with the upwardly extending arms 96 connected together by a bar 97 which may be apertured at one end as shown for connection with an operating cable adapted to be carried to any convenient point of access. It is apparent that when the bar 97 is pulled by the cable both of the levers 95 will swing and project their cams 86 downwardly to simultaneously operate the pins 84 and release both latches and force the lower cover 91 into open position.

The cover 91 may also be provided at an intermediate point with a transverse upstanding curved bead or rib 98 adapted to enter the annular slot 93 of the flare and cooperate with the bead 94 in maintaining the flare against shifting or vibration while in the casing 90.

It is obvious that various changes and modifications may be made in the details of construction and design of the above specifically described embodiment of this invention without departing from the spirit thereof, such changes and modifications being restricted only by the scope of the following claims.

What is claimed is:

1. A combined flare and launching means therefor comprising a flare body, a tube surrounding the body to protect the same, a cap carried on the upper end of the tube and having centering means engaging the flare to hold the same releasably in the tube, a bottom cap fitting on the tube and engaging the flare to support it and hold it in the tube, a socket member from which the flare body may be launched, means for securing the tube to the socket member, frangible means for locking said securing means, and means carried by the socket member operable upon the lower cap and said securing means to break said frangible means and remove the cap from the tube and release the flare body.

2. A combined flare and launching means therefor, comprising a flare body, a tube enclosing the body to protect the same, a socket member adapted to be mounted on an aeroplane or the like, means for securing said tube to the socket member to support the flare body in position for launching, a releasable cap mounted on the lower end of the tube for maintaining the

flare therein, a latch carried by the tube engaging the cap to lock the latter in closed position, frangible means for holding the latch against movement, and a combined latch releasing cap ejecting means and breaking means for said frangible means carried by the socket member for operation on the latch and the cap of the tube when the latter is mounted on the socket member to release the flare from the tube.

3. A combined flare and launching means therefor, comprising a flare body, a combined carrying case and launching tube disposed about the body, an upper cap on the carrying tube having a depressed central portion engaging the upper end of the flare to releasably hold it in the tube, a lower cap fitting in the tube and engaging the flare to support it and hold it in position in the tube, said lower cap and tube having means at one side to hingedly support the lower cap at said side, a latch carried by the tube at the opposite side thereof engaging the lower cap to secure the same in closed position, frangible means for holding the latch against accidental release, a socket member for receiving the launching tube to hold the same and the flare in position, and a combined latch releasing breaking means for said frangible means and lower cap ejecting means carried by the socket member for retracting the latch to release the lower cap and for engaging the lower cap to swing the latter free of the launching tube and the flare body.

4. A combined flare and launching means therefor, comprising a flare body, a tube surrounding the body to protect the same, a cap fitting on the upper end of the tube and having a central depressed portion engaging the flare body to center the same in the tube, a lower cap fitted to the lower end of the tube and engaging the flare body to center the same in the tube and support the flare body, a latch slidably mounted on the outer side of the tube and movable inwardly into interlocking engagement with the lower cap to secure the same on the tube, said latch having an opening therethrough and said lower cap having a flange adapted to register beneath the opening, a socket member from which the flare may be launched, means for securing the tube in the socket member, a pin carried by the socket member in line with the opening offset outwardly from the opening in the latch when in locking position, said pin having an inclined lower surface portion, and means for depressing the pin to move the inclined surface portion thereof through the opening in the latch to release the latter and for moving the pin downwardly against the flange of the lower cover to forcibly eject the latter from the lower end of the tube.

5. A combined flare and launching means therefor, comprising a flare body, a tube enclosing the body to protect the same and having an outstanding flange at its lower end, a cap fitted to the lower end of the tube and having a flange thereabout, the flanges of the tube and cap having interengaging means at one side of the tube for hingedly supporting the cap thereon, the flange of the tube having at its opposite side an opening therethrough in register with the flange of the cap, a latch slidably mounted on the tube flange over said opening and having an opening therein adapted to be moved partially out of register with the opening in the tube flange when the latch is in locking position, said cap having a slot therein for receiving said latch to lock the cap in the tube, a socket member

- adapted to receive said tube flange therebelow, a pin carried by the socket member having a tapered lower end in register with the opening in the tube flange and in partial register with the opening in the latch when in locking position, and means for depressing said pin for first retracting said latch from the cap to release the latter and for further movement through the opening in the tube flange to forcibly eject said cap from the tube.
- 5 6. A combined flare and launching means therefor, comprising a flare, a horizontal case for carrying the flare and launching the same in horizontal position, said case open at its lower side, a cover hinged to the case for the lower end thereof adapted to support the flare in the case, latching means connected to the case and engageable with the cover for holding the same closed, a socket member for receiving the carrying case to support the same and the flare, and at least one combined latch releasing and cover ejecting means carried by the socket member for retracting the latching means to release the cover and for engaging the cover 10 to swing the same into open position and free the flare from the carrying case.
- 15 7. A combined flare and launching means therefor, comprising a flare, a case for carrying and launching the flare in a horizontal position, means for centralizing the flare in the case and supporting the latter against endwise and lateral movement in the case, and a releasable cover on the bottom of the case for supporting the flare therein, said cover having 20
- 25
- 30

centralizing and supporting means at its inner side for engaging the flare and cooperating with said like means in the case for holding the flare in place.

8. A combined carrying case and launching tube for a flare, comprising a tube for the flare and having an outstanding flange, a cap removably fitted to the lower end of the tube for supporting a flare in the tube, a latch lever pivoted on said flange and adapted to be moved into interlocking engagement with the cap and the tube to hold the same on the tube, frangible means for holding said latch against movement and a removable locking device for the latch engaging the latch and the flange to retain the latch from release from the cap to hold the flare in the tube during handling, transportation and storage.

9. A combined flare and launching means therefor, comprising a flare body, a protecting member about the body, a flare supporting member releasably secured to said protecting member, a laterally movable locking member carried by said protecting member and engaging said supporting member to releasably lock said supporting member in position, a frangible means holding said locking means against movement, and a locking means releasing member operable to simultaneously move said locking means into released position, break said frangible means and forcibly move said supporting member into released position.

SAMUEL WILEY.
